J. R. LEWIS.
EXCAVATOR.

No. 97,783.

Patented Dec. 14, 1869.

United States Patent Office.

JOHN R. LEWIS, OF PIPER CITY, ILLINOIS.

Letters Patent No: 97,783, dated December 14, 1869.

IMPROVED EXCAVATOR.

The Schedule referred to in these Letters Patent and making part of the same.

To all whom it may concern:

Be it known that I, JOHN R. LEWIS, of Piper City, in the county of Ford, and State of Illinois, have invented an Improved Excavator; and I do hereby declare that the following is a full, clear, and exact description thereof, which will enable those skilled in the art to make and use the same, reference being had to the accompanying drawings, and letters marked thereon, making a part of this specification, in which—

Figure 1 is a perspective representation of my improved excavator.

Figure 2, a broken plan view of parts appertaining thereto.

Figure 3, a perspective view of the plow removed from its beam.

Figure 4, a bottom view of the plow and lower part of the elevator.

The present invention relates to an improvement in that class of excavators which is mounted upon wheels, and arranged, by suitable mechanism, to elevate the earth, and deposit it at one side of a ditch, or a place that is being graded; and

Its nature consists in the novel construction of the plow, and the novel manner in which it is combined with the elevator.

Also, in the peculiar arrangement of the devices employed to operate the shovel and elevator, as the whole is hereinafter fully described.

B B' represent the running gear of an ordinary farm-wagon, provided with a box-frame, A A', for supporting the working parts of my invention.

The rear part, A', of the frame is made at one end to project over one of the side pieces A, and to extend down far enough to provide a suitable support for one end of a plow-beam, T. The part projecting downward being slotted out, allows the beam to be raised or lowered between the depending standards J' K', which are provided with holes V V', in which a pin, V, is put to hold the rear end of the beam in a fixed position when adjusted to the required height.

A beam, H, is fastened to the forward part of the side pieces A A', and it projects over one of the frame-pieces A, on the same side that the part A' projects, far enough to support depending standards L K, between which the forward end of the beam T is held. Said beam being provided with two lugs U, bearing against the forward sides of the standards, is held firmly against the draught of the plow D, and the standards L K being strengthened by a brace, M, bearing against the side piece A, are held in vertical positions.

In order to provide means within the convenient reach of the operator, for raising and lowering the forward end of the beam T, a wheel, I, is placed above the

beam; and on its shaft, which has bearings in the beam H, and a standard, J, attached to the standard L, is wound a rope, x, which fastens to said beam, so that when the wheel is turned, the beam will be raised or lowered, as the case may be.

Any suitable catch may be used to lock the wheel in any given position, if desired.

The plow consists of a point, D, landside E, standard F, and mould-board, W'. The latter having its outer wing at W, as shown at figs. 1 and 3, curved up, prevents the earth, as it is being carried up toward the elevator X, from falling off.

The mould-board and landside are connected together by means of an iron brace, g, securely bolted to the aforesaid parts, and pivoted to a strap, t, which is rigidly attached to the shoe-plate X of the elevator, and has a series of holes made through it for the convenience of so changing the position of the bolt, with which the brace g is fastened, that the landside D may be set to or from the lower end of the elevator, as shown at fig. 4.

The plow has its shank bolted fast to the beam at F, thus supporting the front lower corner of the elevator, the other end of the elevator being supported by means of a chain, Z, fastened to a pin in the top of said beam.

The elevator consists of two stiles O, strengthened by a tie, N, and shoe-plate, X. The upper ends of these stiles are held to projecting beams G G', fastened to side pieces A A, by means of clevises Q, figs. 1 and 2, which pass over said beams, and have holes through their lower ends, to receive a pivot-rod, P.

The lower end of the elevator is provided with a roller, Y, and the outer ends of the beams G, with a roller, C, around which an ordinary endless belt, for carrying the earth up from the plow, is to be put.

The roller C is driven by means of a bevel-pinion, S, which, in turn, is driven by a bevel-pinion, h, fig. 2, fastened to the same shaft as the pinion m, which is driven by a cog-wheel, R, fastened to the hub of one of the hind wheels of the wagon.

To enable the pinion S to be thrown out of gear with the pinion h, the journal of roller C, in the beam G', has a slotted bearing, whereby, when a key, b', fig. 2, is driven into a tapering mortise in said beam, the pinion S will be moved outward.

The device, as described, will be found very convenient for cutting any depth, from one to eight inches, in an easy and satisfactory manner; and as any ordinary farm-wagon can be used for the running gear, a very great saving is made in the cost, as the excavating-attachments can readily be removed by lifting off the frame A A'.

Having thus described my invention,

What I claim, is—

1. The plow, provided with a mould-board turned up at W, to carry earth on to the elevator, in combination with the brace *g*, shoe-plate *X*, and connecting-plate *t*, as set forth.

2. The combination of the plow D W F E, brace *g*, plates *t* *X*, stiles O O, roller Y, and beams T and G' as described.

3. The combination of the frame A A', depending

standards J K and L K, cross-beam T, provided with lugs U, wheel I, rope Z, and chain, Z, for supporting and adjusting the plow and lower ends of the elevator, as and for the purpose specified.

J. R. LEWIS.
